STEAM TURBINE APPARATUS

Robert Hertl, Lansdowne, Pa., assignor to Westinghouse Electric & Manufacturing Company, East Pittsburgh, Pa., a corporation of Pennsylvania

Application April 29, 1941, Serial No. 390,863

4 Claims. (Cl. 253—69)

My invention relates to an elastic-fluid turbine wherein the rotor and the cylinder define chambers separated by blading and it has for an object to provide apparatus of this character in which the equilibrium passage or conduit connecting the chambers includes a passage formed in a nozzle vane or block so that the length of the turbine may be shortened and its critical speed raised.

With a large steam turbine of the high-pressure and high-temperature type having a full peripheral impulse stage, the dummy may be located so close to the impulse wheel that there is little, if any, space left for an equilibrium space or passage. To answer this need, in accordance with the present invention, the nozzle block or a nozzle vane, or a partition wall or rib, is formed to provide a portion of the equilibrium passage, it being remembered, of course, that an equilibrium pipe or passage is necessary to avoid excessive end thrust and consequent thrust bearing trouble or failure. If, with a full peripheral admission turbine, conventional practice is followed, it becomes necessary to lengthen the turbine sufficiently so that the dummy is spaced from the impulse wheel adequately to accommodate the equilibrium pipe or passage; however, increasing the length of the turbine lowers the critical speed, involves increased expense and waste of space, and, because of critical speed requirements, may make the design of a large turbine prohibitive.

A further object of the invention is to provide an impulse stage having a single row of moving blades with an equilibrium passage or conduit for connecting together the spaces at the inlet and outlet sides of the blades and wherein one or more nozzle vanes of the stage accommodate portion or portions of the equilibrium passage.

These and other objects are effected by my invention as will be apparent from the following description and claims taken in accordance with the accompanying drawing, forming a part of this application, in which:

Fig. 1 is a fragmentary, longitudinal, sectional view of a portion of a turbine showing the improved equilibrium passage applied thereto;

Figs. 2 and 3 are enlarged detail sectional views, and are taken along the lines II—II and III—III of Figs. 1 and 2, respectively;

Figs. 4, 5, 6 and 7 are detail sectional views showing a modified form in which a vane itself has a portion of the equilibrium passage;

Fig. 8 is a detail sectional view showing a special nozzle vane having greater axial length in 55

order to accommodate a portion of the equilibrium passage; and

Fig. 9 is a detail sectional view of a Rateau stage having an equilibrium passage connecting the spaces at opposite sides of the wheel, the passage having portions thereof formed in nozzle vanes.

Referring now to the drawing more in detail, in Fig. 1 there is shown a turbine rotor 10 and a cylinder 11 defining chambers 12 and 13 separated by the blading 14 supplied with steam at suitable velocity by means of nozzle passages 15 defined by nozzle vanes 16 carried by the nozzle block 17.

As shown in Fig. 1, the chamber 12 is arranged between the rotor impulse portion 14a carrying the moving blades of the blading 14 and the dummy 18. In order that the dummy may be subjected to the same pressure as that existing in the chamber 13 at the discharge side of the blading 14, it is necessary to provide one or more equilibrium pipes or passages, one being shown. Because of the relatively close spacing of the dummy 18 and the impulse stage in Fig. 1, the nozzle block has a radially-extending passage 20 aligned with radial passages 22 formed in the block 17. The cylinder has a passage 23 formed therein, one end of the passage 23 communicating with space 13 and the other end communicating with the outer radial opening or passage 22. Thus, there is provided, an equilibrium passage having a portion thereof extending radially of and incorporated in the nozzle block.

As shown in Figs. 1 and 2, the nozzle block portion 20 of the equilibrium passage is provided by a pipe section 21 arranged ahead of the inlet edge 25 of one of the nozzle vanes.

In Fig. 3, there is shown in detail how the component elements of the nozzle block structure are connected together, the inner and outer ends of the vanes 16 being connected to inner and outer portions of the nozzle block 17 in any suitable manner and the pipe 21 having its ends fitting closely portions of the block 17 provided with the aligned passages 22 and preferably being welded, as shown at 26, to the edge of the adjacent outer and inner members of the nozzle block to prevent leakage.

In Figs. 4 to 7, inclusive, there are shown nozzle block structures having vanes 16 defining nozzle passages 15 and wherein one of the vanes is modified so as to incorporate the radial passage portion 20 of the equilibrium passage.

In Figs. 4 and 5, the passage 20 is defined by a pipe 21a incorporated within the structure of

the vane, the ends of the pipe preferably extending through inner and outer portions of the nozzle block and providing the passage portion 20.

In Figs. 6 and 7, the passage 20 is defined by an opening extending longitudinally of the vane, the ends of the passage aligning with radial openings 22 formed in the nozzle block structure 17. The welds 28 provide for sealing of the joint between adjacent ends of the passages 20 and 15.

In Fig. 8, there is shown a further form of the invention representing a combination of the features of Figs. 4 and 6. In this view, one of the vanes 16a has substantially greater axial length than the other vanes, the relatively greater axial length making it possible to provide a passage 20a which is of curved and elongated section.

In Fig. 9, there is shown a form of the present invention particularly suitable for a single row impulse or Rateau turbine stage. This type of stage incorporates alternately arranged nozzle vane structures or diaphragms 29 and turbine discs or wheels 30, each diaphragm 29 preceding a wheel 30 having nozzle vanes 31 providing nozzle passages for supplying steam at suitable velocity to the blades or buckets 32 carried by the succeeding disc or wheel 30. In this view, there is shown one of the discs or wheels 30 with diaphragms preceding and succeeding the latter. As there may be a difference in pressure between the steam inlet and outlet sides of the blades or buckets 32, it is desirable to provide an equilibrium passage to assure of the maintenance of identical pressures at opposite sides of the wheel or disc. Accordingly, the diaphragms at either side of the wheel or disc 30 have radial passages 22a formed therein and aligned and operatively continuous with the radial passages 20b formed in the vanes 31. The outer ends of the passages 22a are connected by an axially-extending passage 23a having portions thereof formed in the diaphragms and in the cylinder structure 11a.

The expression "nozzle vane structure," as used herein embraces the nozzle block and the vanes collectively; and, when it is stated that such structure has a passage formed therein, this covers either formation of the passage in a vane or in a separate pipe or structure.

While the invention has been shown in several

forms, it will be obvious to those skilled in the art that it is not so limited, but is susceptible of various other changes and modifications without departing from the spirit thereof, and it is desired, therefore, that only such limitations shall be placed thereupon as are specifically set forth in appended claims.

What I claim is:

1. In a turbine, a cylinder and a rotor providing chambers therebetween, blading separating the chambers, nozzle vane structures cooperating with the blading, and means including a passage formed in a nozzle vane structure to provide an equilibrium passage connecting the chambers.
2. In a turbine, a cylinder and a rotor providing chambers therebetween, blading separating the chambers, a nozzle block including nozzle vanes defining nozzle passages for supplying elastic fluid to the blading, and means including a passage formed in the nozzle block to provide an equilibrium passage connecting the chambers.
3. In a turbine, a cylinder and a rotor providing chambers therebetween, blading separating the chambers, a nozzle block attached to the cylinder and including vanes defining nozzle passages for supplying elastic fluid to the blading, and means including communicating passages formed in the structures of the cylinder and of the nozzle block and extending axially of the structure of the cylinder and radially of the structure nozzle block to provide an equilibrium passage connecting the chambers.
4. In a turbine, a cylinder and a rotor providing chambers therebetween; an impulse stage including stationary and moving blades carried by the cylinder and by the rotor, respectively, and a nozzle block provided with nozzle passages for supplying elastic fluid to the blades; a dummy construction cooperating with the rotor and with the cylinder and providing for the imposition of steam thrust on the rotor; one of said chambers being arranged between the dummy construction and said stage at the elastic-fluid inlet side of the latter and the other chamber being arranged at the outlet side thereof; and means including a passage formed in the nozzle block to provide an equilibrium passage connecting the chambers.

ROBERT HERTL.
